Primary Examiner — Mark Goodwin*(74) Attorney, Agent, or Firm* — Corinne R. Gorski**CLAIM**

The ornamental design for a screening media, as shown.

DESCRIPTION

FIG. 1 is a perspective front view of a first embodiment of a screening media,

FIG. 2 is a perspective top view thereof,

FIG. 3 is a perspective back view thereof,

FIG. 4 is a back view thereof,

FIG. 5 is a long side view thereof

FIG. 6 is a front view thereof, and

FIG. 7 is a short side view thereof,

FIG. 8 is a perspective front view of a second embodiment of a screening media,

FIG. 9 is front view thereof,

FIG. 10 is a long side view thereof,

FIG. 11 is a short side view,

FIG. 12 is a perspective front side view thereof,

FIG. 13 is a perspective back side view, and

FIG. 14 is a back view thereof.

FIG. 15 is a perspective front view of a third embodiment of a screening media,

FIG. 16 is a front view thereof,

FIG. 17 is a long side view thereof,

FIG. 18 is a short side view thereof,

FIG. 19 is a perspective front side view thereof,

FIG. 20 is a perspective back side view thereof; and,

FIG. 21 is a back view thereof.
